COMMUNICATION AND POWER SYSTEM

Hugo W. Wahlquist, Mount Vernon, N. Y.

Application April 5, 1938, Serial No. 200,059

19 Claims. (Cl. 171—97)

This invention relates to communication and power systems, such as rural distribution systems in which the power transmitted is small and in which telephone and power systems parallel each other so that the latter, by capacity and inductive effects, interferes with the transmission of speech over the telephone line. The invention is also applicable to systems in which power lines interfere with telegraph lines operating with alternating current.

This application is a continuation-in-part of my application Serial No. 152,899, filed July 10, 1937.

When a telephone line runs parallel to a power line, the magnetic and electric fields of the power line induce currents in the paralleling telephone line. These induced currents consist of the fundamental frequency (usually 60 cycles) and the harmonics of the fundamental frequency, such as 180, 300, 420 cycles, etc.

The chief noise producing factors are frequently the higher odd harmonics, the odd harmonics being those with a frequency 3, 5, 7, etc., times that of the basic frequency of the power lines, which is usually 60 cycles. The ones that are chiefly objectionable are those from 9 upwards. Much can, therefore, be accomplished by reducing the higher harmonics in the power line. However, there still remains induced current of 60 cycles and also of the lower harmonics which, although they have frequencies below that required for the efficient transmission of the ordinary voice (500 upwards), are well within the audible range, and, if not largely eliminated, interfere with voice transmission. Although the telephone receiver has a relatively low response to the fundamental 60-cycle current, the presence of considerable 60-cycle current in the receiver is disturbing. Such current tends to distort speech transmission rather than drown out the speech signals by the simple production of noise. It follows that substantially complete elimination of interference with voice transmission can be accomplished only by first reducing the higher harmonics in the power line and then eliminating the effect of low frequency current either by acoustical means or by bypassing the 60-cycle and lower harmonic currents induced in the telephone line, so that they do not flow through the receiver, or at least flow therethrough to a much lesser extent than they would do normally.

Telephone and power systems vary greatly as do the effects of one on the other, so that in some cases it may be sufficient either to reduce

the higher harmonics in the power line or to reduce the flow of induced 60-cycle and lower harmonic currents through the receiver.

Harmonics in a power line may originate from either the power supply system, such as a direct coupled generator or a transformer, or from particular types of loads, such as a rectifier, connected across the line. In the first case the harmonic currents flow away from the supply system and in the second case toward the supply system as well as in the opposite direction, if the rectifier or the like is not at the end of the line.

The present application is chiefly concerned with power lines fed from a single supply source, as distinguished from a power network fed from a plurality of sources.

The application of my improvements with which I am chiefly concerned is to rural power lines which have considerable capacitance and supply loads which are largely resistance, so that the line and loads combined have a capacitance in excess of inductance for a frequency of about 500 cycles, usually considerably more. As the supply source is always inductive it follows that at some frequency the inductance of the supply source and the capacitance of the line become equal and resonance occurs. If such resonant point is adjacent one of the important harmonics a large current may flow.

Under these conditions a large increase occurs in the magnitude of the voltage impressed on the rural line at the frequencies in the neighborhood of the resonant frequency, and there is a consequent large increase in the harmonic charging current in the line. In the majority of cases a substantial portion of the harmonic line current returns in the earth, and, due to the high coupling of this earth return circuit with a paralleling telephone, the induction may be severe. In situations of this character a suitable capacitor connected across the transformer on the rural line side will destroy the resonant condition at the higher harmonic frequency, and, in combination with the transformer and supply line impedances, reduce other high frequency voltages and currents in the rural line.

To reduce harmonics it has frequently been the practice to connect across the line a series of shunts tuned to 660, 780, 1020, 1140, 1380 and 1500 cycles, these being the principal harmonics to be taken care of in the majority of situations.

I have found that, instead of several tuned shunts, one shunt only is necessary, provided that its characteristics bear the proper relationship to the impedance of the power supply system.

Where a plurality of tuned shunts have been used, the designers have considered merely the fact that to obtain resonance at, say, 1020 cycles, the product LC (inductance $\times$ capacity) is fixed, and, hence, as the expensive part of the shunt is the condenser, they have made the condenser as small as practicable in view of the current to be passed through the shunt.

My method of eliminating harmonics does not depend on tuning the shunt to any particular harmonic frequency, but rather on lowering the frequency at which the power supply system and shunt circuit resonates from a frequency above 500 cycles, say 1500, to a frequency below 500, preferably a non-harmonic frequency, such as 250. This latter relationship involves a totally new ratio, viz: shunt capacity to power supply system inductance, instead of the shunt capacity to shunt inductance ratio, as has been used heretofore.

According to my invention, therefore, I take into consideration the inductance of the supply system, referred to hereafter as L_1 , as well as the inductance of the shunt, L_2 . In fact, in many cases very fair results can be obtained with $L_2=0$. In that case there is only one resonant point corresponding to L_1C at around 250 cycles. Where I use shunts with inductance, i. e., where L_2 is not zero, there will be resonance at some frequency within the voice range corresponding to L_2C as well as resonance at 250 cycles corresponding to $(L_1+L_2)C$. Using the old rule of making the condenser as small as practicable, there would be two high resonance points. This follows from the fact that the product $(L_1+L_2)C$ will be only a little greater than L_2C and hence correspond to a resonance point at, say, 900 cycles, instead of 1020 for L_1C , taken alone.

It is better to have inductance as well as capacitance in the shunt to give lower impedance for the higher harmonics than is possible where $L_2=0$ and at the same time retain a resonance point around 250 cycles for $(L_1+L_2)C$.

To obtain the desirable ratio between the inductance of the power supply system and the capacity of the shunt, the $(L_1+L_2)C$ product, where L_1 is the inductance of the supply system and L_2 is the inductance of the shunt in millihenries and C is the capacity of the shunt in microfarads, should preferably be about 400 (resonance at 250) and not greatly less than 125 (resonance at 450). In order to enable a single shunt to cut down all the higher harmonics L_2 should be smaller than L_1 , preferably much smaller. That is a distinguishing feature of my invention, as heretofore L_2 has been larger than L_1 .

The use of a capacitor and reactor in combination so designed and connected across a power line supplied from a supply system of high inductance and having, by virtue of such inductance, a normal resonance at a frequency between 500 and 2000 cycles, may reduce the resonant frequency of the power line below 500 cycles. A capacitor designed as above described destroys the natural resonance between the line and power supply system at the higher harmonics. It is desirable to select a capacitor having such capacity with respect to the inductance of the power supply system that it forms a shunt circuit resonant to a frequency which does not correspond with that of any important harmonic in the power circuit. For example, the important harmonics are 180, 300, 420, etc. By setting the capacitor to resonate at 250 there is no tendency to increase markedly the 180 or 300 harmonics.

Some increase occurs, but the increase is far less than it would be were the capacitor to be resonant to either 180 or 300 cycles. At all events, there is a great reduction in the telephone influence factor (which is an overall weighting of all harmonics present) although one or two of the lower harmonics may be increased.

One of the advantages of my invention is that not only will a single shunt take care of a plurality of harmonics but it will also take care of high frequency asynchronous currents, such for example as 930 cycles, which lies between the 15th and 16th harmonics.

Capacitors have been used for correcting power factor, and, when so used, are connected in shunt near the load and have their capacities adjusted so that at 60-cycle current the impedance of the capacitors is substantially equal to the impedance due to the inductance of the load. Capacitors so located and having the impedances stated, frequently increase the undesired (from the point of view of noise) higher harmonic currents in the line between the point at which power is supplied and the point of connection of the capacitor.

When a capacitor is used in the present invention with a power supply source of high inductance it is usually located near the point of power supply. With capacitors connected near the load, the harmonics in the power line have to travel the full length of the line from the generator or transformer to the load, which often is beyond the section of line which parallels the telephone line.

The placing of a capacitor across the power line, while it reduces the higher harmonics, may increase the lower harmonics. Hence, while the over-all noise reduction may be large, there may well be such noise remaining, due to the original low harmonic currents as well as those created by the capacitor, as to make necessary the use of the receiver circuit shunt connection.

In a three-phase, three-wire power line, the usual arrangement involves three capacitors connected between the various pairs of wires. In a three-phase, four-wire power line, usually a capacitor is connected between each of the phase wires and the neutral.

With a three-wire arrangement in which the line is supplied directly by a generator instead of through a transformer, and the generator is provided with a grounded neutral, the capacitors may be connected between the wires and ground.

In a three phase line having single phase extensions unequally distributed among the three phases the resonant point of each line does not occur at the same frequency and as a result, when capacitors are not used, there is apt to be a large amount of harmonics flowing through the ground. Hence, in such lines, in addition to reducing the higher harmonic voltages in the power line, the capacitors have a balancing effect on important harmonics so that a smaller proportion of them appear as ground return components. It is the ground currents which have a particularly high influence on the adjacent telephone line.

In isolated single phase power lines supplied with power through a single phase transformer it is advantageous to use two capacitors connected in series across the power line, with a connection to ground from the conductor connecting the two capacitors. The ground connection may include a detector adapted to indicate when one of the conductors of the power line is grounded accidentally.

In the case of multi-grounded lines supplying

loads which create harmonics a capacitive shunt adjacent the source of supply will not prevent earth currents of harmonics generated by such loads. To reduce the latter a second capacitive shunt may be placed near the load. I have found that in the case of a uni-grounded line the load harmonics act on the impedance of the supply system and cause harmonic voltages to appear and these voltages produce ground currents due to the capacity of the line to the ground. Where a capacitive shunt is used adjacent the supply system these load harmonics are prevented from building up harmonic voltages at such point and thereby are unable to create harmonic ground currents.

In one actual case the noise produced in a telephone line by a three-phase power line was reduced about 25 to 1 by the installation of a capacitor across the power line, the remaining noise being principally due to the lower harmonic components. In the above actual case, the line was three-phase, 12,000 volts for 14 miles and had 20 miles of single-phase extensions. The specified noise reduction was accomplished by connecting a 30 kva. capacitor (1.74 microfarads) between each phase wire and neutral. As, however, in the above case, the telephone line was grounded, it was also necessary to apply a shunt receiver-condenser connection to the subscriber set or equivalent acoustical means to complete the noise reduction.

Heretofore, in the ordinary form of receiver of a local battery subscriber set commonly used in country areas, the receiver has been so connected that, except for the very small part which flows through the high-impedance ringer, all current flowing through the line, including all the induced 60-cycle and lower harmonic current, passes through the receiver. According to the present invention, the telephone line is connected to the return circuit independently of the receiver to permit low frequency current to enter the return circuit without passing through the receiver. This connection includes inductive means for transferring voice current potential to the receiver to cause voice current to flow therethrough. A condenser is connected in series with the receiver to filter out low frequency current. This has the result of by-passing more or less completely both the 60-cycle induced current and the lower harmonic induced currents, while allowing the currents which are essential to the transmission of speech to pass through the receiver without substantial loss. This suppression of the induced currents is effective on both electrically induced and magnetically induced currents; and this new arrangement is also effective in suppressing in the receiver, currents resulting from differences in ground potential.

For the usual commercial subscriber set a condenser having a capacitance of around 1 microfarad is ordinarily satisfactory. This sized capacitance will reduce the 60-cycle current in the receiver about 200 or 300 to 1, the 180-cycle current about 25 to 1, 300 cycles about 10 to 1, and 420 cycles about 4 to 1.

Various suitable applications of the invention to electrically coupled telephone and power systems are illustrated diagrammatically, by way of example, in the accompanying drawing, the usual ringing mechanism being omitted for sake of simplicity. In the drawing:

Fig. 1 illustrates a combination of power and local battery telephone lines embodying the present invention;

Fig. 2 shows an alternative form of power line and subscriber set circuit to that of Fig. 1;

Fig. 3 shows a power line capacitor circuit suitable for an isolated single-phase line; and

Fig. 4 shows a power line capacitor circuit suitable for an unbalanced three phase line.

As shown in Fig. 1, 10 represents a multi-grounded power line supplying energy to a second power line 11 by a transformer 12. A telephone line running parallel to and in close proximity 10 to the power line 11 is indicated by 13. Across the line 11, preferably before it comes near the telephone line, is connected a capacitor 14 for reducing the higher harmonic currents in the line 11 beyond its point of connection. 15

While, as shown in Fig. 1, the capacitor shunt may be pure capacity, conditions often arise in which it may be desirable to place an inductance in the shunt, as indicated by 32 in Fig. 2. One case is where there is a prominent frequency between 500 and 2000 cycles and it is therefore desired to make the shunt alone resonant at such frequency, while making the shunt plus supply transformer resonant below 500 cycles. 20

Again, as the frequency goes up, there comes a point at which the distributed inductances and capacitances of the power line, in effect, neutralize each other, so that the line acts as if it had resistance only. For a line open at the far end, this point is known as the $\frac{1}{4}$ wave length (series resonant) frequency. This point may be reached, for example, when the frequency is around 1500 cycles for a line 27 miles long. As the pure resistance of the line is very low, this frequency is a resonant point at which currents of very considerable magnitude may flow. If, now, the capacitor shunt has inductance and capacity so proportioned that at the line resonant frequency they are equal and opposite, a substantial short circuit is created for such resonant 40 currents.

A subscriber's set is indicated diagrammatically at A and includes an induction coil having primary and secondary coils 18 and 19, respectively, a battery 20, transmitter 21, hook switch 22 and 45 ground connection 23. The usual signaling equipment, such as a magneto and ringer, are, for simplicity, omitted.

Around the primary 18 is a shunt circuit 25 in which the receiver 26 and a condenser 27 are 50 connected in series. The condenser 27 is of such capacity that it offers great reactance towards 60-cycle and lower harmonic currents and little reactance towards those currents by which speech is efficiently transmitted. As a result, low frequency current induced in the telephone line 13 flows to ground chiefly through the secondary 19, hook switch 22 and ground connection 23. 55

The capacitive reactance of the condenser 27 should be of the same order of magnitude as the 60 inductive reactance of the receiver at frequencies around 1000 to 1500 cycles. When this relationship holds, the total impedance (capacitive and inductive reactances plus resistance) of the receiver and condenser in series is less than the impedance of the receiver alone. As a rule, the condenser should have a capacity between 0.5 and 1.5 microfarads. 65

In the form of construction shown in Fig. 2, an auto-transformer 30 is used; otherwise the set 70 is the same as that of Fig. 1. For simplicity, the hook switch 22 has been omitted.

In the case of isolated, i. e., ungrounded, lines the circuit shown in Fig. 3 may be used to advantage. In that case two capacitors 36 are 75

placed in series and the conductor connecting them is connected to ground by a lead 37. A ground detector D may be applied to the lead 37 for the purpose of indicating accidental 5 grounding of one or other of the conductors 11 of the power line.

As previously explained, where a single-phase extension is connected to a three-phase line, the 10 system is unbalanced. The deleterious effects of this unbalancing is eliminated to a very large extent by means of capacitors connected as shown in Fig. 4. In this case the three-phase conductors 40 and neutral 41 are fed from a suitable 15 supply source by a delta-star transformer 42. A single phase extension is indicated by 43. Three capacitors 44 are connected between the conductors 40 and the neutral 41.

As already pointed out, a single-phase ungrounded line, as shown in Fig. 2, provided with 20 a single shunt adjacent the source of supply does not ordinarily require another shunt near a load, indicated at L out on the line which generates harmonics, to cut down the harmonics in the earth resulting from such load. The above is 25 true even though the load is a rectifier generating very large amounts of harmonics, provided the line is of the single-phase ungrounded type.

The invention is also applicable to telephone 30 circuits which are metallicized, i. e., do not use a ground return for speech transmission. The susceptiveness of metallic telephone lines to induced noise is much lower than that of circuits operating over one wire with ground return whether or not the lines are transposed to 35 reduce noise induction between the wires of the circuit. However, when transpositions are used, they do not change the noise voltages to ground of the line, and these latter voltages react on the unbalances in the telephone line with resulting 40 noise. Such unbalances may exist in the form of three contacts, high resistance joints in the line, or the presence of ringers connected from the line wires to ground in cases where the ground return ringing system is used.

45 The capacitors may be used to prevent interference with A. C. telegraphic systems. To increase the number of telegraphic messages which may be sent over a single circuit, the telegraphic sending apparatus comprises a series of generators of varying frequencies and the receiving apparatus comprises a corresponding series of circuits each tuned to one generator frequency. The dots and dashes are produced by interrupting the flow of current of the desired frequency. 50 If currents of the same frequency are induced by a power line, there is a continuous, instead of an interrupted, flow of current which interferes with the transmission of the message.

55 Capacitors may also be used with single-wire ground-return power systems in the same way that they are used with a double-wire single-phase line. In the single-wire system the capacitors are connected to earth instead of to another wire.

60 65 What is claimed is:

1. A power line system with a power factor not greatly less than unity fed from a transformer having a single capacitive shunt having high capacity relative to inductance connected across 70 the power line adjacent the transformer to reduce a plurality of the higher harmonics in the power line.

2. A power line system having a capacitive shunt connected across the power line to reduce 75 a plurality of the higher harmonics in the power

line, the impedance of the shunt being substantially equal to that of the power supply source at a frequency below 500 and markedly different from the fundamental frequency and also the lower harmonics in the system. 5

3. A power line system having a capacitive shunt connected across the power line to reduce the higher harmonics in the system, the impedance of the shunt being such that the system as a whole is resonant at a frequency below 500 10 and markedly different from the fundamental frequency and also lower harmonics in the system.

4. In combination with a power line supplied from a supply system having a high inductance 15 and having, by virtue of such inductance, a normal resonance at a frequency between 500 and 2900 cycles, a capacitive shunt across the power line having constants such that the resonant frequency of the power line and supply system is 20 reduced to below 500 cycles to reduce the harmonics in the line above 500 cycles.

5. In combination with a power line grounded at the source of supply only and a load on such line generating harmonics, a single capacitive 25 shunt having high capacity relatively to inductance across the line adjacent the source of supply for said line for reducing a plurality of the higher harmonics in the ground arising from both the source of supply and the load. 30

6. In combination with an isolated single phase power line supplied with power through a single phase transformer, two capacitors connected in series across the power line to reduce the higher harmonics therein and a connection to ground 35 from the conductor connecting the two capacitors.

7. The combination as in claim 6, in which the ground connection includes a detector adapted to indicate when one of the conductors 40 of the power line is grounded accidentally.

8. In combination with a power line and load having a combined capacitive reactance in excess of inductive reactance at a frequency of about 500 cycles and fed from a single source, 45 a capacitor shunt having high capacity relatively to inductance connected across the power line to reduce a plurality of the higher harmonics in the power line.

9. In combination with a power line supplied from a supply system by a transformer, a shunt connected across the power line, such shunt having both capacitance and inductance, the capacitive and inductive reactances being equal at some frequency above 500 cycles and so proportioned 55 with respect to the combined inductance of the transformer and supply system that the circuit through the transformer in series with the shunt has a resonant point below 500 cycles.

10. A power line system having a capacitive 60 shunt connected across the power line to reduce a plurality of the higher harmonics in the power line, the product $(L_1+L_2)C$, where L_1 is the inductance of the supply system and L_2 is the inductance of the shunt in millihenries and C is 65 the capacity of the shunt in microfarads, being not greatly less than 125.

11. A power line system having a capacitive shunt connected across the power line to reduce a plurality of the higher harmonics in the power 70 line, the product $(L_1+L_2)C$, where L_1 is the inductance of the supply system and L_2 is the inductance of the shunt in millihenries and C is the capacity of the shunt in microfarads, being of the order of magnitude of 400. (not drawn) 75

12. In combination with a power line, a supply system therefor having inductance, and a shunt connected across the power line to reduce the higher harmonics therein and having both 5 capacitance and inductance, the capacitive and inductive reactances of the shunt alone being equal at some frequency well above 500 cycles, the capacitive reactance of the shunt being equal to the combined inductances of the supply system and shunt at a frequency well below 500 cycles, and the inductance of the shunt being much lower than that of the supply system.
13. The combination as in claim 12, in which the capacitive and inductive reactances of the 15 shunt alone are equal at a frequency near that of one of the most prominent harmonics in the power line.
14. The combination as in claim 12, in which the capacitive reactance of the shunt is equal to 20 the combined inductances of the supply system and shunt at a frequency well within the range of 180 to 300 cycles.
15. The combination as in claim 12, in which the capacitive and inductive reactances of the 25 shunt alone are substantially equal at the $\frac{1}{4}$ wave length frequency of the power line.
16. In combination with a grounded three-
- phase power line having single phase extensions unequally distributed among the three phases, a capacitive connection between each phase wire to ground to balance the harmonics and reduce the volume of harmonics flowing through the 5 ground.
17. In combination with a three-phase four-wire power line system, a capacitive shunt between each line and the neutral, the impedance of the shunts being such that the system as a 10 whole is resonant at a frequency below 500 and markedly different from the fundamental frequency and also the lower harmonics in the system.
18. In combination with a three-phase four-wire power line system with a power factor not greatly less than unity, a capacitive shunt between each line and the neutral to reduce a plurality of the higher harmonics in the system.
19. A power line system having a load thereon 20 of a type creating harmonics, a capacitive shunt near the point of supply of power to the power line to reduce harmonics originating in the source of power supply, and a second capacitive shunt near the harmonic-generating load to reduce 25 harmonics originating in such load.

HUGO W. WAHLQUIST.
